CLAIM

The ornamental design for a display screen or portion thereof with graphical user interface, as shown and described.

DESCRIPTION

The file of this patent contains at least one drawing executed in color. Copies of this patent with color drawings will be provided by the Office upon request and payment of the necessary fee.

FIG. 1 is a front view of the first image of a first embodiment of a display screen with static user interface showing our new design.

FIG. 2 is a front view of the first image of a second embodiment of a display screen with static user interface showing our new design.

FIG. 3 is a front view of the first image of a third embodiment of a display screen with static user interface showing our new design.

FIG. 4 is a front view of the first image of a fourth embodiment of a display screen with static user interface showing our new design.

FIG. 5 is a front view of the first image of a fifth embodiment of a display screen with static user interface showing our new design.

FIG. 6 is a front view of the first image of a sixth embodiment of a display screen with static user interface showing our new design.

FIG. 7 is a front view of the first image of a seventh embodiment of a display screen with static user interface showing our new design.

FIG. 8 is a front view of the first image of an eighth embodiment of a display screen with static user interface showing our new design.

FIG. 9 is a front view of the first image of a ninth embodiment of a display screen with static user interface showing our new design.

FIG. 10 is a front view of the first image of a tenth embodiment of a display screen with static user interface showing our new design.

(Continued)

FIG. 11 is a front view of the first image of an eleventh embodiment of a display screen with static user interface showing our new design.

FIG. 12 is a front view of the first image of a twelfth embodiment of a display screen with static user interface showing our new design.

FIG. 13 is a front view of the first image of a thirteenth embodiment of a display screen with static user interface showing our new design.

FIG. 14 is a front view of the first image of a fourteenth embodiment of a display screen with static user interface showing our new design.

FIG. 15 is a front view of the first image of a fifteenth embodiment of a display screen with static user interface showing our new design.

FIG. 16 is a front view of the first image of a sixteenth embodiment of a display screen with static user interface showing our new design.

FIG. 17 is a front view of the first image of a seventeenth embodiment of a display screen with static user interface showing our new design.

FIG. 18 is a front view of the first image of an eighteenth embodiment of a display screen with static user interface showing our new design.

FIG. 19 is a front view of the first image of a nineteenth embodiment of a display screen with static user interface showing our new design.

FIG. 20 is a front view of the first image of a twentieth embodiment of a display screen with static user interface showing our new design.

FIG. 21 is a front view of the first image of a twenty-first embodiment of a display screen with static user interface showing our new design.

FIG. 22 is a front view of the first image of a twenty-second embodiment of a display screen with static user interface showing our new design; and,

FIG. 23 is a front view of the first image of a twenty-third embodiment of a display screen with static user interface showing our new design.

The dash-dot-dash line showing of a display screen or portion thereof, forms no part of the claimed design. The dashed elements form no part of the claimed design.
